UNITED STATES PATENT OFFICE.

GEORGE W. MILLER, OF WAYNESVILLE, NORTH CAROLINA.

BURNER.

Application filed June 22, 1923. Serial No. 647,186.

To all whom it may concern:

Be it known that I, GEORGE W. MILLER, a citizen of the United States, residing at Waynesville, in the county of Haywood and State of North Carolina, have invented new and useful Improvements in Burners, of which the following is a specification.

This invention relates to a lamp burner, the general object of the invention being to provide means whereby the chimney part of the burner can be lifted off the wick carrying part so that the wick can be lighted without removing the chimney.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a view of a lamp showing my invention in use.

Figure 2 is an enlarged detail view showing the two parts of the burner separated.

Figure 3 is a sectional detail view through one of the guiding means.

Figure 4 is a plan view of the wick carrying part.

Figure 5 is a plan view of the chimney carrying part.

Figure 6 is a perspective view of a finger engaging part.

In these views 1 indicates the wick carrying part of the burner and 2 the chimney carrying part. A pair of oppositely arranged rods 3 are carried by the brackets 4 formed on the part 1 and tubular guides 5 are formed on the part 2 for receiving said rods. Thus the part 2 is slidably arranged on the rods. The guides are carried by ears 6 on the part 2 and finger engaging parts 7 have horizontal portions which are provided with grooves 8 which engage the ears so that the finger parts are slidably connected with the ears. Said hori-

zontal parts are also provided with elongated openings 9 which receive the tubular guides. A spring 10 is carried by the part 2 at the inner side thereof and the ends of the spring engage pins 7' formed in the horizontal portions of the finger engaging parts. This spring tends to hold the finger engaging parts in the outer positions with the horizontal portions pressing against the rods so that the part 2 is frictionally held against movement on the rods. When it is desired to move the part 2 the finger parts are pressed inwardly so as to remove the friction and thus permit the part 2 to be adjusted on the rods. Thus the part 2 and the lamp chimney can be easily and quickly raised to permit the wick to be raised and then lowered. In this way it is not necessary to remove the chimney.

I prefer to make the chimney holding arms 11 with spring parts 12 to hold the chimney in place by spring pressure so that there is but little danger of the chimney being accidentally knocked off the lamp.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A lamp burner of the class described comprising a wick carrying part and a chimney carrying part, rods carried by the wick carrying part, ears on the chimney carrying part, tubular guides depending from the ears and through which the rods pass, an angle-shaped finger engaging part slidably mounted on each ear by having guides formed on its horizontal part engaging the ear, said horizontal part having an elongated opening therein for receiving the tubular guide and a spring having its ends engaging portions of the finger engaging parts for frictionally holding them against the tubular guides.

In testimony whereof I affix my signature.
GEORGE W. MILLER.
